UNITED STATES PATENT OFFICE.

ED HAMBLIN, JR., OF WOODWARD, OKLAHOMA.

POOL-TABLE POCKET GUARD.

Application filed January 13, 1923. Serial No. 612,463.

To all whom it may concern:

Be it known that I, ED HAMBLIN, Jr., a citizen of the United States, residing at Woodward, in the county of Woodward and 5 State of Oklahoma, have invented a new and useful Pool-Table Pocket Guard, of which the following is a specification.

This invention has reference to pool table attachments, and aims to provide novel 10 means to be positioned over the usual metallic pocket support of a pool table for guarding the usual leather covering against the impact of a ball entering the pocket.

Another object of the invention is to 15 provide a device of this character constructed of such material that the device may be readily and easily positioned over the pocket support, the material being of such resiliency as to grip the support and 20 prevent accidental displacement thereof.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, may be made within the scope of what is claimed, without departing 30 from the spirit of the invention.

Referring to the drawing:—

Figure 1 is a perspective view disclosing a portion of a pool table, the device forming the subject matter of the present 35 invention, being applied.

Figure 2 is a sectional view through the support and guard.

Figure 3 is a rear elevational view thereof.

Figure 4 is a plan view of the guard.

Referring to the drawing in detail, the reference character 5 designates the usual metallic pocket supporting member which is covered with a leather protecting member 6 formed with openings to accommodate the

pocket 7 which is constructed in the usual 45 and well known manner.

The guard forming the essence of the invention is formed preferably of trunk fiber and pressed into such forms as to conform to the curvature of the pocket support 5. 50 As shown, this guard includes a curved section 8 formed with a curved depending flange 9 formed along the forward edge thereof, there being provided a curved flange 10 at the rear of the section 8 and 55 adapted to conform to the curvature of the pocket support 5.

Formed integral with the flange 10 are the depending ears 11 which are formed with openings 12 to receive the adjacent 60 threads or cords 13 of the pocket to secure the guard in position. It is to be understood that while I have shown and described a guard, the guard is constructed of such material as to not only cushion the blow 65 directed to the pocket support 5, by a ball entering the pocket, but at the same time possess such resilient qualities as to grip the pocket support 5 by eliminating the necessity of employing springs or other metallic means for securing the guard in position. 70

What is claimed as new is:—

A pocket guard for game tables including a body portion adapted to be positioned 75 over the pocket iron of a game table, said body portion including flanges, ears formed at the ends of one of the flanges, said ears being apertured to receive the cord of which the pocket is formed to secure the guard to 80 the pocket iron.

In testimony that I claim the foregoing as my own, I have hereto affixed my signature in the presence of two witnesses.

ED HAMBLIN, JR.
